UNITED STATES PATENT OFFICE.

EDWIN C. BIGELOW, OF NEW YORK, N. Y.

TEMPORARY BINDING DEVICE.

1,035,769.

Specification of Letters Patent. Patented Aug. 13, 1912.

Application filed September 6, 1911. Serial No. 647,842.

To all whom it may concern:

Be it known that I, EDWIN C. BIGELOW, a citizen of the Dominion of Canada, residing at New York, in the county of New York

5 and State of New York, have invented new and useful Improvements in Temporary Binding Devices, of which the following is a specification.

This invention relates to temporary binding devices, and it has for its object to produce a simple and efficient device whereby a plurality of loose leaves may be separably assembled in bound form.

10 A further object of the invention is to produce a temporary binding device which shall be especially adapted to the assembling together of pamphlets, such as magazines and the like, in bound form.

15 A still further object of the invention is to produce a simple and improved temporary binding device in which the leaves or pamphlets assembled may be quickly and conveniently interchanged, and in which such leaves, pamphlets and the like may be 20 fully exposed to inspection when the binding device is open.

With these and other ends in view which will readily appear as the nature of the invention is better understood, the same consists in the improved construction and novel 25 arrangement and combination of parts which will be hereinafter fully described and particularly pointed out in the claims.

30 In the accompanying drawings has been illustrated a simple and preferred form of the invention, it being, however, understood that no limitation is necessarily made to the precise structural details therein exhibited, but that changes, alterations and modifications 35 within the scope of the claims may be resorted to when desired.

In the drawings,—Figure 1 is a perspective view of a loose leaf binder constructed in accordance with the invention, the same 40 being shown open for the addition or removal of inserts. Fig. 2 is a perspective view of the supporting plate and allied parts, detached, from the back of the binder. Fig. 3 is a sectional view, enlarged, taken 45 through the back of the binder adjacent to one end of the supporting plate and showing the supporting arms engaged by the cams of the rock shaft. Fig. 4 is a similar view showing the arms disengaged by the 50 cams of the rock shaft. Fig. 5 is a top plan view of the device, showing the binder open

for the insertion or removal of inserts. Fig. 6 is a sectional view taken on the line 6—6 in Fig. 5. Fig. 7 is a sectional view taken on the line 7—7 in Fig. 5.

60

Corresponding parts in the several figures are denoted by like characters of reference.

In the construction of the improved binding device a back member B constructed of wood or other suitable material is provided, 65 the same having covers C, C hingedly connected therewith. The external face of the back member B may be rounded, as shown, to present the appearance of the back of a book. The internal face of said back member is plane and is provided at suitable distances from its upper and lower edges with transverse grooves or channels 1, 1 between which a plate 2 is firmly secured upon the back member by fastening devices, such as 70 screws 3. The plate 2 is provided at the side edges thereof adjacent to the hingedly supported cover members C, C with tubular bearing portions 4 and 5 formed by suitably bending or curving the material of which the 75 plate 2 is composed, said tubular bearing portions being projected inwardly from the plane face of the back member 1, as shown.

Supported for oscillation in the tubular bearing 4 of the plate 2 is a rock shaft 6 80 having radially extending arms 7 at the ends thereof, said arms being bent at right angles to the shaft, which latter is thus secured in its bearing in such a manner as to preclude the possibility of longitudinal displacement. The tubular bearing 5 contains a rod 8 constituting a rock shaft having at one end thereof a handle 9 whereby it may be rocked or oscillated. Said rod or rock shaft is also provided adjacent to the ends 90 of the plate 2 with notches or recesses 10 forming reduced cam portions 10', said notches being exactly of proper depth to admit of the passage of the ends of the arms 7 when the rock shaft 8 is positioned with 100 the recesses 10 facing the shaft 6 having the arms 7. It will be obvious that by partly rotating the shaft 8 by means of the handle 9 the arms may be locked with reference to the shaft 8 and the back of the binder by 105 engagement with the cam portions 10'.

In connection with the improved binding device, I employ a plurality of tabs D consisting of elongated strips of metal provided midway between their ends with laterally 110 extending ears or lugs 11 having apertures 12, said ears or lugs being also provided

with sharp edges 13 which will readily penetrate ordinary printing paper.

In practice, the magazines or pamphlets that are to be bound, and one of which is shown at 14, are provided with two of the tabs D, the same being inserted between the folds of the magazine or pamphlet so as to cause the apertured lugs 11 to project at the back thereof, said apertured lugs being 10 strung upon the arms 6 of the binding device, while said arms are positioned as shown in Fig. 1, the free ends of said arms being subsequently carried into engagement with the notched rock shaft 8, which latter 15 is then oscillated so as to cause the cam portions 10' to engage the free ends of the arms 7 which are thus secured in position within the transverse grooves 1 of the binder, the latter being of sufficient dimensions to freely 20 accommodate the apertured lugs 11 of the tabs D.

It is obvious that any number of magazines or pamphlets within the capacity of the binder may be strung or mounted in 25 position upon the arms 7 and that such magazines or pamphlets may be freely and fully inspected by opening the binder, there being absolutely no obstruction to the full and complete opening of the leaves. It is 30 also evident that additions or removals may be readily made at any time and that the magazines or pamphlets in the binder will be firmly secured without regard to the number thereof.

35 It is evident that when the device is to be adapted to a binder for loose leaves the tabs D may be secured upon the leaves by cement or mucilage or in any other suitable and convenient manner. In this event the tabs 40 may also be made of strong paper or cardboard.

Having thus described the invention, what is claimed as new, is:—

1. In a binding device, a back member

having hinged covers, a plate secured upon 45 the inner face of the back member and having tubular bearings at the side edges thereof, a rock shaft supported in one of said bearings and having radially extending arms, and a rod supported for oscillation 50 in the other bearing and having reduced cam portions registering with the arms, said arms being of an extreme length which is less than the distance between the rock shaft and the reduced cam faces of the rod to 55 permit said arms to clear said faces in one position of the rod, which latter in another position will obstruct the arms.

2. In a binding device, a back member having hinged covers and transverse grooves 60 upon the inner face thereof, a plate secured between and adjacent to the grooves and having tubular bearings at the side edges thereof, a rock shaft supported in one of said bearings and having radial arms, elongated 65 tabs having apertured ears engaging the arms and accommodated in the transverse recesses, and a rod supported for oscillation in the other bearing and having reduced cam portions registering with the 70 arms.

3. In a binding device, a back member having transverse grooves upon the inner face thereof, a rock shaft supported adjacent to one side edge of the back member 75 and having radial arms, means for securing the free ends of said arms adjacent to the opposite edge of the back member, and tabs having laterally extending apertured ears engaging the arms, said ears being accommodated in the transverse grooves.

In testimony whereof I affix my signature in presence of two witnesses.

EDWIN C. BIGELOW.
